UNITED STATES PATENT OFFICE

2,420,665

SHOE MACHINE

Bernhardt Jorgensen, Marblehead, Mass., assignor to United Shoe Machinery Corporation, Flemington, N. J., a corporation of New Jersey

Application March 26, 1945, Serial No. 584,763

6 Claims. (Cl. 12—1)

1

This invention relates primarily to machines for use in the manufacture of shoes, although it will be recognized that in some aspects it is not thus limited in its applicability. The invention is herein illustrated as applied to a toe-lasting machine constructed generally as disclosed in United States Letters Patent No. 2,324,509, granted on July 20, 1943, on an application of mine, but modified in some respects as shown in later disclosures of mine including especially Letters Patent No. 2,337,558, granted on December 28, 1943, and No. 2,391,461, granted on December 25, 1945.

It has been proposed heretofore, as disclosed in the last-mentioned Letters Patent, to position shoes in shoe machines such, for example, as the above-mentioned toe-lasting machine by means engaging the insole of each shoe in a hole or indentation previously formed in the insole in predetermined relation to the edge of the shoe bottom. Means for punching such a hole or indentation in the insole is herein shown as attached to the frame of a toe-lasting machine of the above-mentioned character and operated by power from that machine. The latter is a fluid-operated machine provided with means for maintaining fluid under pressure at a source of supply only intermittently at the times required for the operation of the machine on successive shoes, the pressure at the source being reduced substantially to zero at the end of each cycle of operations of the machine. In order that the insole-punching means may be operated, if desired, when the lasting machine is not in operation, the present invention provides an organization including an accumulator which receives fluid from the above-mentioned source when the fluid is under pressure and stores the fluid for use in thus independently operating the insole-punching means. With respect to this feature the invention, in its broader aspects, is to be understood as not limited to insole-punching means or to lasting machines.

The invention will now be more particularly described with reference to the accompanying drawings and thereafter pointed out in the claims.

In the drawings,

Fig. 1 is a view in front elevation of the greater portion of a toe-lasting machine such as disclosed in the above-mentioned Letters Patent, as modified for purposes of this invention;

Fig. 2 is a plan view on an enlarged scale of the insole-punching mechanism shown in Fig. 1, with the parts in their starting positions;

2

Fig. 3 shows the insole-punching mechanism in elevation as viewed from the right with reference to Fig. 2;

Fig. 4 is a section on the line IV—IV of Fig. 2;

Fig. 5 shows in elevation a portion of the insole-punching mechanism as viewed from the left with reference to Fig. 2, with the parts in operative relation to a shoe shown in section;

Fig. 6 is a section on the line VI—VI of Fig. 2;

Fig. 7 is a vertical sectional view of the accumulator for storing fluid to operate the insole-punching mechanism, and of parts associated therewith;

Fig. 8 is a plan view of the accumulator and associated parts;

Fig. 9 is a section on the line IX—IX of Fig. 7;

Fig. 10 shows partly in section and partly in elevation one of the valve mechanisms of the lasting machine;

Fig. 11 is a view in front elevation illustrating how the shoe prepared by the insole-punching mechanism is positioned in the lasting machine, the shoe being shown in section;

Fig. 12 is a section on the line XII—XII of Fig. 6; and

Fig. 13 is a diagrammatic view of the fluid-pressure generating and controlling means of the lasting machine with the accumulator associated therewith.

The toe-lasting machine herein shown, as fully disclosed in the previously mentioned Letters Patent, is provided with a plurality of fluid-operated instrumentalities which operate on the shoe in the course of a cycle of power operations of the machine, these instrumentalities including a toe former 2 (Fig. 1) which wipes the toe end of the upper heightwise of the last and a pair of wipers 4 (Figs. 1 and 11) which wipe the margin of the toe end of the upper inwardly over an insole on the last into position to be secured to the insole by cement applied to the shoe at a predetermined time in the operation of the machine. As disclosed in Letters Patent No. 2,391,461, the shoe is presented by the operator with the bottom of the forepart of the insole in engagement with a plate 6 provided with a spur 8 which enters a small hole or indentation previously formed in the forepart of the insole to position the shoe lengthwise and laterally. Associated with this spur there may or may not be side gages such as shown in said Letters Patent. Substantially at the beginning of the power operation of the machine the shoe is clamped against the plate 6

55 by the upward movement of a toe rest 10. Oper-

ative movements are imparted to the toe rest 10, the toe former 2, the wipers 4, and other operating instrumentalities by cylinder-and-piston devices not herein shown in detail, these devices being supplied with fluid, preferably oil, under pressure from a manifold 12 (Fig. 13). Admission of the fluid to the different devices and exhaust of the fluid therefrom are controlled by valves some of which are shown at 14 in Fig. 13, these valves being controlled, as disclosed especially in Letters Patent No. 2,337,558, by fingers 16 (Fig. 1) mounted on a rotatable drum 18 which is driven by a piston 20 mounted in a cylinder 22. Admission of fluid from the manifold to this cylinder and exhaust of the fluid therefrom are controlled by a valve 24 which is moved initially by the operator to admit the fluid. It will be understood that a cycle of operations of the machine corresponds to one complete revolution of the drum 18.

Fluid is supplied to the manifold 12 from a sump or reservoir 26 by a pump 28 which is continuously driven by an electric motor 30 and forces the fluid through a pipe 31 leading to the manifold. When the machine is not in operation, however, the fluid returns freely from the manifold to the reservoir 26 through a valve 32 without developing any substantial pressure in the manifold. This valve, which is substantially like the valves 14 and 24, is shown in detail in Fig. 10. It is a sleeve valve mounted to slide on a tube 34 which is in communication with the manifold, the tube having therein a partition 36 which divides one end portion thereof from the other. At one side of the partition are a plurality of ports 38 and at the other side thereof a plurality of ports 40. Formed in the valve is an annular chamber 42 through which, when the valve is in its initial position, the ports 38 and 40 are in communication with one another to permit the escape of the fluid from the manifold. To stop such escape of the fluid and thus to cause pressure to be developed in the manifold the valve 32 is moved toward the left (Fig. 10) to cover the ports 38, the excess fluid delivered by the pump then returning to the reservoir 26 past a spring-controlled relief valve 43 (Fig. 13) which controls the pressure in the manifold. As fully disclosed in Letters Patent No. 2,324,509, this movement of the valve 32 is effected through a treadle-operated rod 44 acting on a lever 46 which is pivoted at 48 and serves to impart the movement to the valve through a swinging arm 50 connected to the valve. The valve is retained in the position to which it is thus moved by means of a latch 52 in engagement with a shoulder 54 on a block 56. At the end of the cycle of operations one of the fingers 16 on the drum 18 acts on an arm 58 connected to the latch 52 to withdraw the latch and release the lever 46, whereupon the valve 32 is returned to its initial position, to cause the pressure in the manifold to fall substantially to zero, by a spring 60 acting on the arm 50.

To provide the insole with the small hole or indentation to receive the spur 8 of the lasting machine, there is supported on an arm 62 fast on the right-hand side of the frame of the machine near the front thereof what is herein termed insole-punching mechanism. This mechanism includes a casting 64 on the front end portion of which are pivotally mounted two rolls 66 (Figs. 1, 2 and 6) arranged to engage the bottom face of the forepart of the insole in locations spaced apart widthwise of the shoe when

the shoe is presented thereto bottom upward by the operator. A third roll 68 is pivotally mounted on a plate 70 secured to the lower face of the casting 64 and is arranged to engage the insole 5 in a location nearer the toe end thereof than the rolls 66 and substantially midway between the sides of the toe. The three rolls thus serve as a shoe rest and facilitate movement of the shoe in a toeward direction after the operator has 10 presented the shoe against them. Such movement of the shoe is limited by engagement of its toe-end face with an arm 72 which serves as an end gage for the shoe and serves also another purpose hereinafter described. Further to position the shoe laterally and angularly in proper relation to a punch hereinafter described for punching the hole in the insole, there are provided two pairs of side gages 74 and 76 comprising respectively arms 78 and 80 arranged to extend lengthwise of the shoe and pivotally mounted 20 on studs 82 on the casting 64. The two gages 74 are arranged to act on the shoe at the opposite sides of the forepart in the vicinity of its ball portion, and the two gages 76 are arranged to act thereon at the opposite sides of its toe portion. 25 Each arm 78 carries a stud 84 on which is pivotally mounted a small block 86 faced with leather or other appropriate material 88 for contact with the shoe, the block being movable about the stud 84 short distances limited by its contact with the arm 78 to permit it to adjust itself to the shoe. Each arm 80 has fast thereon a block 90 (Fig. 4) faced with leather 92 or other material and provided with an upwardly extending stem 94 secured to the arm by a nut 96. Integral with the 30 arms 78 are arms 98 (Fig. 12) extending inwardly toward each other and connected together by gear teeth so that the arms 78 will swing equal distances in unison toward or from the shoe. Similarly the arms 80 have integral therewith 35 inwardly extending arms 98 connected together by gear teeth so that the arms 80 also will swing equal distances in unison toward or from the shoe. Mounted in one of the arms 98 is a plunger 100 (Fig. 6) pressed by a spring 101 against one face of the casting 64, the spring tending to swing the two arms 78 outwardly away from each other. Similarly a spring 102 controlling a plunger 103 (Fig. 12) mounted in one of the 40 arms 98 tends to swing the two arms 80 in outward directions. Also integral with one of the arms 78 is a third arm 104 provided with a roll 106 in engagement with the outer end of a piston 108 movably mounted in one end of a cylinder 110 formed in the casting 64. Another similar piston 108 movably mounted in the other end of the cylinder 110 is engaged on its outer end by a roll 112 supported by an arm 114 which is integral with one of the arms 98. Each piston 108 is provided on its outer end with a flange 116 arranged to engage the casting 64 to limit inward movement of the piston in the cylinder 110. It will, therefore, be evident that the flanges 116 limit the outward swinging movements of the gage 45 arms 78 and 80 under the influence of the springs 101 and 102. For adjusting the arms 78 toward or from each other the arm 104 is provided with an eccentric stud 118 on which the roll 106 is mounted, and similarly the roll 112 is mounted 50 on an eccentric stud 120 (Fig. 4) on the arm 114 for adjusting the arms 80 toward or from each other.

From the above description it will be evident that the two gages 74 are operated by one of the pistons 108 and the two gages 76 by the

other piston, each pair of gages being thus movable independently of the other pair of fluid admitted to the cylinder 110 in the common chamber between the pistons so that all the gages are moved as far as required properly to centralize the shoe between them. Operating fluid is conducted to the cylinder 110 through a pipe 122 from an accumulator 124 (Fig. 7) which includes a casting 125 supported on the side frame of the lasting machine below the insole-punching mechanism, the accumulator being charged with fluid from the source of supply of the lasting machine as hereinafter more particularly described. Admission of fluid from the accumulator to the pipe 122 is controlled by a valve 126 mounted in a chamber 128 at one end of the accumulator casting 125. This valve is essentially of the same construction as the previously mentioned valve 32 (Fig. 10). That is, it is a sleeve valve slidably mounted on a tube 130 which is divided by a partition 132, one end of the tube communicating with the accumulator and the other end with the pipe 122. When the valve is in its initial position, as shown in Fig. 7, the accumulator is not in communication with the cylinder 110 and the latter is open to exhaust through the pipe 122 and ports 134 in the tube 130, these ports communicating with the chamber 128 from the upper portion of which the fluid is returned to the reservoir 26 through a pipe 136. Movement of the valve 126 toward the left (Fig. 7) opens communication through an annular chamber 138 in the valve between the ports 134 and other ports 140 in the tube 130, thus admitting fluid from the accumulator to the pipe 122. Such movement of the valve is effected through a lever 142 (Figs. 7 and 9) pivotally mounted on a stud 144 which is supported by a lug 146 extending downwardly into the chamber 128 from a cover plate 148 over the chamber, this lug supporting also a splash shield 147 positioned over the ports 134. At its lower end the lever is provided with a pin 150 extending into a groove 152 in the valve. The valve is held normally in its initial position by a spring 154 in engagement at one end with a washer 156 which bears on a lug 158 extending upwardly from the cover plate 148 and in engagement at its other end with a block 160 pivotally mounted on the upper arm of the lever 142 which extends through a slot in the cover plate. A rod 162 is pivotally mounted on the lug 158 and extends through the spring and the block 160. The upper end of the lever 142 is connected by a link 164 to the armature 166 of a solenoid 168 supported on the top of the casting 125. Accordingly, when the electrical circuit of the solenoid is closed the lever 142 is operated to move the valve 126 into position to admit fluid from the accumulator to the pipe 122. Such closing of the electrical circuit is effected by the pressure of the toe-end face of the shoe against the previously mentioned arm 12 (Fig. 6) when the shoe is presented by the operator to the insole-punching mechanism. This arm is pivotally mounted on a pin 170 on the casting 64 and is controlled by a spring 172 which is positioned between a lug 174 on the hub portion of the arm and a portion of the casting 64 and tends to swing the arm in a clockwise direction with reference to Fig. 6. Movement of the arm in this direction is limited by its engagement with an edge face 176 of the casting 64. In this manner the normal position of the arm is determined. Pivotally mounted at 180 on the lower end of

the arm is a block 182 which is further controlled as hereinafter described and has adjustably secured to its lower face a plate 184. One edge of this plate is arranged to engage a knob 186 fastened to a switch member 188 which extends into a switch box 190 on the casting 64 and by inward movement against the resistance of a spring (not shown) is arranged to close the electrical circuit of the solenoid. The switch, not shown in detail, is one of a well-known type requiring only a very short movement of the switch member 188 to close the circuit. Movement of the arm 12 by the shoe is limited by a screw 191 which is threaded in the lug 174 and is arranged to engage the casting 64. Accordingly the arm is effective not only as a switch-closing member but also as an end gage for the shoe to determine the distance from the end of the toe of the hole punched in the insole.

To form the hole or indentation in the insole there is provided a punch 192 (Figs. 5 and 6) comprising a pin vertically movable in a bore in the casting 64 and having a conically pointed lower end for engagement with the insole. On the upper end of the pin is formed a plunger 194 movable downwardly in another bore in the casting against the resistance of a return spring 196. The plunger 194 is engaged on its upper end by a hardened contact piece 198 carried by a member 200 which is pivotally mounted on a pin 202 on the casting 64. The member 200 is provided with two downwardly extending fingers 204 between which is a pin 206 fast on the casting 64 for limiting movements of the member in opposite directions by engagement with the fingers. As the parts are shown in Fig. 6, the member 200 is held by the spring 196 in the position determined by engagement of the pin with one of the fingers, the punch 192 being retracted above the insole of any shoe presented to the machine. When the punch is operated to punch the hole in the insole its movement is limited by engagement of the pin 206 with the other finger 204 of the member 200, its movement being only sufficient to punch the hole part way through the insole, as illustrated in Fig. 5.

The movement of the member 200 to operate the punch 192 is effected by mechanism which will now be described. Pivotally connected by a pin 208 to this member is a block 210 to which is rigidly connected a rearwardly extending rod 212, the block and the rod being parts of a self-contained hammer unit 213. The rod 212 extends through a cylinder 214 provided with a roll 216 which rests on a flat face 218 formed on a portion of the casting 64. This face accordingly supports the hammer unit against the force of gravity. Surrounding the rod 212 inside of the cylinder 214 is a spring 220. Mounted on the rod is a washer 222 which is seated against inwardly extending flanges 224 (Fig. 2) of the cylinder 214 and itself provides a seat for one end of the spring. The other end of the spring is engaged by a washer 226 also mounted in the cylinder 214 and confined on the rod 212 by a nut 228. A narrow rearwardly extending portion 230 (Fig. 2) of the block 210 lies in a vertical slot in the front end of the cylinder 214 between the flanges 224 to permit relative movements of the block and the cylinder in directions lengthwise of the cylinder while preventing the cylinder from turning relatively to the block. It will be evident that the spring 220 by its pressure on the washer 222 tends to move the cylinder forwardly toward the block, and by the

spring the cylinder is thus held normally in a relation to the block determined by engagement of portions of the block with the front end face of the cylinder, as illustrated in Fig. 2. Pivotally mounted on a pin 232 (Fig. 6) on the casting 64 is a lever 234 on the upper end of which is secured a hardened wear plate 236 arranged to engage the edge of a similar plate 238 secured to the cylinder 214. Also mounted on the upper end of the lever 234 is a roll 240 engaged by one end of a piston 242 movably mounted in a cylinder 244 formed in the casting 64. The piston carries a screw 246 which by engagement with the inner end wall of the cylinder limits the inward movement of the piston in the cylinder. Mounted in the lower end portion of the lever 234 is a plunger 248 which engages one face of the casting 64 and is controlled by a spring 250. This spring, therefore, tends to swing the lever 234 in a counterclockwise direction with reference to Fig. 6 and to move the piston 242 to its limit of inward movement determined by the screw 246. Operating fluid is admitted to the inner end of the cylinder 244 from the previously mentioned cylinder 110 through a passage 252. By the action of the fluid the piston 242 is forced outwardly and swings the lever 234 in a clockwise direction as far as permitted by engagement of the lower end of the lever with that face of the casting 64 which is engaged by the plunger 248. In the course of this movement of the lever the plate 236 by engagement with the plate 238 first imparts to the cylinder 214 lengthwise movement in a direction away from the block 210 and thereby compresses the spring 220 through the action of the washer 222 on the spring, this movement of the cylinder not being of sufficient extent to cause the rearwardly extending portion 230 of the block 210 to be withdrawn from the slot in the cylinder. Prior to the completion of the movement of the lever 234 the plate 236 slips downwardly past the edge of the plate 238, thus releasing the cylinder 214, whereupon the spring 220 impels the cylinder suddenly in the reverse direction until its front end strikes against the block 210. By its momentum the cylinder thus acts as a hammer to swing the member 200 and thereby to impart operative downward movement to the punch 192 against the resistance of the spring 196, the movement of the member 200 being limited by the pin 206 as hereinbefore described. The passage 252 connecting the cylinder 110 to the cylinder 244 is a restricted passage such as to retard the flow of the fluid to the cylinder 244 and thereby to insure that the gages 74 and 76 will properly position the shoe before the punch is operated. In the return of the parts to starting positions the hammer unit is lifted by the engagement of the plate 236 with the plate 238 to permit the return of the lever 234.

Pivotaly connected at its lower end to the previously mentioned block 182 (Fig. 6) is a rod 254 which extends upwardly through an opening in a rearwardly extending arm 256 of the member 200, and confined on this rod by nuts 258 is a washer 260 having a lower curved face engaging a similar face on the arm. It will be evident that when the member 200 is moved as above described to operate the punch the arm 256 is swung in an upward direction, and through the connection between this arm and the block 182 the block also is swung upwardly and carries the plate 184 away from the knob 186 on the switch member 188. In response to such release of the

switch member the electrical circuit of the solenoid 168 is broken, whereupon the valve 126 is returned to its initial position by the spring 154, thereby releasing the fluid from the cylinder 110 and from the cylinder 244 connected thereto. This permits the gages 74 and 76 to be swung away from the shoe by the springs which control them and permits the piston 242 and the lever 234 to be returned by the spring 250. It will be understood that when the shoe is removed the arm 72 is returned by the spring 172, thus permitting the plate 184 again to be moved downwardly into operative relation to the knob 186 by the block 182. To insure such return of the plate and the block there is mounted in the arm 72 a spring-pressed plunger 262 in engagement with the top face of the block.

The accumulator 124 from which the fluid is obtained for operating the insole-punching mechanism includes a piston 264 movably mounted in a cylindrical chamber 266 in the casting 125. This piston is controlled by a spring 268 which abuts at its outer end against a plate 270 held in fixed relation to the casting 125 by screws 272. The outer end of the spring is centralized relatively to the plate 270 by a circular plate 274 which is positioned within the spring and is provided with a projection 276 extending into an opening in the plate 270. It will be understood that the piston 264 is movable outwardly in the chamber 266 against the resistance of the spring by the pressure of the fluid admitted to the chamber. The fluid for thus charging the accumulator is conducted to the chamber 266 from the source of supply of the lasting machine through a pipe 278 which, as shown in Fig. 13, is tapped into the pipe 31 leading from the pump 28 to the manifold 12. In the pipe 278 is a check valve 280 which prevents any return flow of the fluid from the accumulator. It will be understood that the accumulator is thus charged at any time when the manifold 12 contains fluid under pressure greater than the pressure of the fluid in the accumulator, and that when the pressure in the manifold is reduced to zero at the end of a cycle of operations of the lasting machine the accumulator remains charged so that the insole-punching mechanism may be operated, if occasion requires, when the lasting machine is idle. Preferably the capacity of the accumulator is such that the insole-punching mechanism may thus be operated three or four times without any recharging of the accumulator, although ordinarily it need be operated only once to prepare the first shoe for presentation to the lasting machine prior to the starting of that machine. Thereafter the insole-punching mechanism will ordinarily be used to prepare a shoe for presentation to the lasting machine while the latter is operating on a shoe previously prepared. To prevent the piston 264 from blocking the opening from the pipe 278 to the chamber 266 there is secured to the piston a plate 282 having an annular extension 284 of smaller diameter than the piston for engaging the end wall of the chamber 266 to limit the inward movement of the piston, this plate serving also to hold in place packing 286 for preventing leakage of the fluid. Any of the fluid that may escape past the piston is received in an annular groove 288 in the casting 125 and is conducted from this groove back to the reservoir 26 through a pipe 290.

The manner of operation of the construction described will now be briefly summarized. Before presenting the first shoe to the lasting ma-

chine the operator presents it to the insole-punching mechanism, the accumulator 124 being already charged with fluid under pressure. The operator thus presents the shoe to the insole-punching mechanism with the bottom of the forepart of the insole in engagement with the rolls 66 and 68 and pushes the shoe lengthwise against the end gage member 72. The pressure of the end face of the shoe against this member operates the switch member 188 to close the electrical circuit of the solenoid 168, whereupon the solenoid operates the valve 126 to admit fluid from the accumulator to the pipe 122 leading to the cylinder 110. The pressure of the fluid in this cylinder then moves the pistons 108 in outward directions and thereby swings the pairs of side gages 74 and 76 inwardly to position the shoe between them relatively to the punch 192, as illustrated in Fig. 12. At the same time fluid passes from the cylinder 110 to the cylinder 244 through the restricted passage 252 for imparting outward movement to the piston 242. The movement of this piston swings the lever 234 to retract the cylinder 214 against the resistance of the spring 220 through engagement of the plate 236 with the plate 238, the cylinder being released to the action of the spring when the plate 236 is moved far enough to disengage it from the plate 238. The spring then operates the cylinder 214 as a hammer which by impact on the block 210 swings the member 200 to impart operative movement to the punch 192, the movement of the punch being limited by engagement of the pin 206 with one of the fingers 204. The punch thus forms a hole or indentation in the bottom of the insole without passing entirely through it, as illustrated in Fig. 5. As the punch is thus operated the arm 256 of the member 200 acts through the rod 254 to swing the block 182 upwardly and thus to release the switch member 188, thereby breaking the electrical circuit of the solenoid. The valve 126 is then returned by the spring 154 to its initial position, closing the outlet from the accumulator and opening the ports 134 to the chamber 128 to permit exhaust of fluid from the cylinders 110 and 244. The side gages are then returned by the springs 104 and 102, moving the pistons 108 inwardly in the cylinder 110 as far as permitted by their flanges 116, and the piston 242 is returned by the spring 250 through the lever 234, the hammer unit 213 being lifted by this lever to permit the plate 236 to pass the plate 238. Immediately after its operation the punch is returned by the spring 196 which imparts corresponding return movement, limited by the pin 206, to the member 200 and to the hammer unit. The return of the member 200 permits the plate 184 to resume its initial relation to the switch member 188 upon return of the gage member 72 by the spring 172 when the operator removes the shoe. The operator then presents the shoe to the lasting machine in position for the spur 8 (Fig. 11) of that machine to enter the indentation in the insole and starts the operation of that machine. In the course of the operation of the lasting machine the accumulator is again fully charged with fluid passing through the pipe 278 from the pressure source of that machine, return flow of the fluid from the accumulator being prevented by the check valve 200. The operator will ordinarily present each shoe, after the first one, to the insole-punching mechanism while the lasting machine is operating on a shoe previously operated on by that mechanism, but the charge of fluid maintained in the accumulator permits

the use of the insole-punching mechanism at any time.

While the insole-punching mechanism is herein shown as operating on a shoe which has already been partially lasted, as is appropriate in view of its attachment to a toe-lasting machine to prepare shoes for immediate presentation to that machine, it will be understood that such mechanism might be used for punching holes in insoles mounted on lasts prior to the mounting of uppers on the lasts.

Novel features of the insole-punching mechanism herein shown and described are claimed in a divisional application, Serial No. 637,621, filed on December 28, 1945.

Having described the invention, what I claim as new and desire to secure by Letters Patent of the United States is:

1. In a shoe machine, the combination with fluid-operated means for operating on shoes including uppers and insoles mounted on lasts, a source of supply of operating fluid, and means for maintaining the fluid under pressure at said source only intermittently at the times required for operating on successive shoes, of additional fluid-operated means for forming an indentation in the insole of each shoe for use thereafter in positioning the shoe relatively to said first-named means, and an accumulator arranged to receive fluid from said source when the fluid is under pressure and to store the fluid for use in operating said additional means.

2. In a shoe machine, the combination with fluid-operated means for operating on shoes including uppers and insoles mounted on lasts each in a cycle of operations of the machine, a source of fluid under pressure for operating said fluid-operated means, and means for reducing the pressure at said source substantially to zero at the end of each cycle, of additional fluid-operated means for forming an indentation in the insole of each shoe independently of said cycle of operations for use thereafter in positioning the shoe relatively to said first-named means, and an accumulator arranged to receive fluid from said source when the fluid is under pressure and to store the fluid for use in thus independently operating said additional means.

3. In a shoe machine, the combination with fluid-operated means for operating on shoes including uppers and insoles mounted on lasts each in a cycle of operations of the machine, a continuously driven pump for supplying fluid under pressure to operate said means, and a valve for automatically reducing the pressure of the fluid delivered by said pump substantially to zero at the end of each cycle, of additional fluid-operated means for forming an indentation in the insole of each shoe independently of said cycle of operations for use thereafter in positioning the shoe relatively to said first-named means, an accumulator arranged to receive fluid delivered by said pump when the fluid is under pressure and to store the fluid for use in thus independently operating said additional means, and a check valve arranged to permit passage of the fluid to the accumulator but to prevent return flow of the fluid.

4. In a shoe machine, the combination with fluid-operated means for operating on shoes each in a cycle of operations of the machine, a source of supply of operating fluid, and means for maintaining the fluid under pressure at said source only intermittently at the times required for operating on successive shoes, of additional fluid-op-

erated means for independently performing another operation on each shoe, and an accumulator arranged to receive fluid from said source when the fluid is under pressure and to store the fluid for use in thus independently operating said additional means regardless of pressure conditions at said source.

5. In a fluid-operated machine, the combination with fluid-operated means for operating on workpieces, a source of supply of operating fluid, and means for maintaining the fluid under pressure at said source only intermittently at the times required for operating on successive workpieces, of additional fluid-operated means for independently performing another operation on each workpiece with the latter in a different position than when operated on by said first-named means, and an accumulator arranged to receive fluid under pressure from said source and to store the fluid for use in thus independently operating said additional means regardless of pressure conditions at said source.

6. In a fluid-operated machine, the combination with fluid-operated means for operating on workpieces each in a cycle of operations of the

machine, a source of supply of fluid under pressure for operating said fluid-operated means, and means for reducing the pressure at said source substantially to zero at the end of each cycle, of additional fluid-operated means for performing another operation on each workpiece independently of said cycle of operations with the workpiece in a different position than when operated on by said first-named means, and an accumulator arranged to receive fluid from said source when the fluid is under pressure and to store the fluid for use in thus independently operating said additional means regardless of pressure conditions at said source.
